LINK AND LEVER CONTROLLED SLIDABLE
JAW WRENCH

Elmer Gren, Elbow Lake, Minn.

Application July 31, 1953, Serial No. 371,538

1 Claim. (Cl. 81—88)

1

This invention relates in general to improvements in hand tools, and more specifically to an adjustable wrench.

The primary object of this invention is to provide an improved adjustable wrench of the clamping type, the adjustable wrench including a handle having disposed at the forward end thereof a fixed head, an adjustable head slidably mounted on the forward portion of the handle, and means carried by the handle for selectively positioning the adjustable head relative to the fixed head.

Another object of this invention is to provide an improved adjustable wrench of the type having a fixed head and an adjustable head, the adjustable head being selectively positioned by means of an actuating member connected thereto by a link, the link being pivotally connected to both the actuating member and the adjustable head and being adjustable in length whereby the fixed head and adjustable head may be selectively clamped on objects of various sizes.

Another object of this invention is to provide an improved adjustable wrench which is of an extremely simple construction and which is formed of readily obtainable material so as to be economically feasible.

A further object of this invention is to provide an improved adjustable wrench which includes a handle having a forward portion having formed at the forward end thereof a fixed head, the handle also including an angularly disposed intermediate portion and an offset grip portion, the angularly disposed portion having pivotally connected thereto an actuating member, the actuating member being connected to a movable head carried by the forward portion of the handle by an adjustable link, the pivotal connections between the link and the movable head and actuating member, and the actuating member and the intermediate portion of the handle being in alignment with the movable head is in a gripping position.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of the adjustable wrench which is the subject of this invention and shows the general construction of same in alternate position of the movable portion

2

of the adjustable wrench being shown in guide lines, portions of the adjustable head of the wrench being broken away and showing sections in order to clearly illustrate the construction thereof;

Figure 2 is an end elevational view of the adjustable wrench, an intermediate portion of the adjustable link being broken away and showing the sections in order to clearly illustrate the manner in which it is adjusted; and

Figure 3 is a transverse sectional view taken substantially upon the plane indicated by the section line 3—3 of Figure 1 which shows the general cross section of the adjustable wrench.

Referring now to the drawings in detail, it will be seen that there is illustrated the adjustable wrench which is the subject of this invention, the adjustable wrench being referred to in general by the reference numeral 10. The adjustable wrench 10 includes an elongated handle which is referred to in general by the reference numeral 12. The elongated handle 12 includes an elongated forward portion 14 which has formed at the forward end thereof a fixed gripping head 16, the gripping head being provided on its rear face with transversely extending teeth 18.

The handle 12 also includes an angularly disposed intermediate portion 20 which is integral with the forward portion 14. Formed integrally with the intermediate portion 20 is a grip portion 22, the grip portion 22 forming the rear part of the handle 12.

Slidably mounted on the forward portion 14 of the handle 12 is an adjustable gripping head which is referred to in general by the reference numeral 24. The adjustable gripping head 24 is complimentary to the fixed gripping head 16 and includes a sleeve portion 26 through which passes the forward portion 14 of the handle 12. The sleeve portion 26 is slightly larger than the cross section of the forward portion 14 so as to permit angular disposition of the adjustable gripping head 24 relative to the handle 12. The adjustable gripping head 24 is normally retained in alignment with the forward portion 14 by a spring 28 disposed within the sleeve 26 bearing against the forward portion 14 of the handle 12 in the manner best illustrated in Figure 1. The adjustable gripping head 24 is provided with transversely extending teeth 30 which are intended to grip an opposite surface of an object to be turned with the wrench 10 from that gripped by the teeth 18.

Pivots connected to the intermediate portion 20 of the handle 12 by a pivot pin 32 is an

actuating member which is referred to in general by the reference numeral 34. The actuating member 34 includes a rear grip portion 36 which is intended to overlie the grip portion 22 of the handle 12 when the adjustable gripping head 24 is in a gripping position. The actuating member 34 includes a bifurcated forward portion formed by a pair of space-parallel legs 38. The legs 38 are disposed on opposite sides of the intermediate portion 20 of the handle 12 and pivotally connected thereto by the pivot pin 32.

Extending between and connecting together the adjustable gripping head 24 and the actuating member 34 is an adjustable link which is referred to in general by reference numeral 40. The adjustable link 40 includes a tubular intermediate portion 42 which is internally threaded and which has threadedly engaged therein externally threaded rod members 44 and 46. The rod members 44 and 46 are oppositely threaded and pivotally connected to the adjustable gripping head 24 and the legs 38 of the actuating member 34 by pivot pins 48 and 50 respectively. The exterior of the tubular portion 42 is knurled to facilitate rotation thereof.

When it is desired to utilize the adjustable wrench 10, the length of the link 40 is varied such that the adjustable gripping head 24 will be disposed closely adjacent an object to be gripped when the same is in engagement with the teeth 18 of the fixed gripping head 16. It will be understood that the link 40 and the actuating member 34 will be in the positions illustrated by dotted lines in Figure 1. Then the actuating member 34 is pivoted to the position shown in 35 forward lines in Figure 1 with the result that the link 40 moves to the position also illustrated in solid lines. This moves the adjustable gripping head 24 toward the fixed gripping head 26 so that an object to be rotated with the adjustable wrench 10 will be firmly gripped between the fixed gripping head 16 and the adjustable gripping head 24. When it is desired to release such an object, the actuating member 34 is again pivoted to the position shown in dotted 45 lines, which results in the rearward movement of both the link 40 and the adjustable gripping head 24 to cause release of such object. It will be

noted that when the adjustable gripping head 24 is in an object gripping position, such as illustrated by side lines in Figure 1, the pivot pins 48, 50 and 32 are in alignment. Due to the alignment of these pivot pins, there is no possibility of the link 40 taking to the position illustrated in dotted lines to cause accidental release of the adjustable gripping head 24 from the member being gripped thereby.

From the foregoing, the construction and operation of the device will be readily understood and further explanation is believed to be unnecessary. However, since numerous modifications and changes will readily occur to those skilled in the art, it is not desired to limited the invention to the exact construction shown and described, and accordingly all suitable modifications and equivalents may be resorted to, falling within the scope of the appended claim.

What is claimed as new is as follows:

A wrench of the character described comprising: a shank including an arcuate intermediate portion terminating in a handle, a stationary jaw on the outer end of the shank, an inner jaw slideable on the shank and cooperable with said stationary jaw, a forked lever pivotally mounted astraddle said arcuate portion of said shank and comprising a handle on one end swingable toward and away from the first named handle, and a longitudinally adjustable link having one end portion pivotally secured between the legs of the forked lever and its other end portion pivotally connected to the inner jaw for operatively and adjustably connecting said lever thereto.
